J. D. PEDERSEN.

FIREARM.

APPLICATION FILED DEC. 13, 1919.

1,410,265.

Patented Mar. 21, 1922.

UNITED STATES PATENT OFFICE.

JOHN D. PEDERSEN, OF JACKSON, WYOMING.

FIREARM.

1,410,265.

Specification of Letters Patent. Patented Mar. 21, 1922.

Original application filed July 30, 1915, Serial No. 42,774. Renewed July 17, 1919, Serial No. 311,689.

Divided and this application filed December 13, 1919. Serial No. 344,675.

To all whom it may concern:

Be it known that I, JOHN D. PEDERSEN, a citizen of the United States, residing in Jackson, in the county of Lincoln and State 5 of Wyoming, have invented certain new and useful Improvements in Firearms, of which the following is a specification.

One object of my present improvements is to furnish an improved trigger-mechanism, or device, especially adapted for use 10 in small arms, particularly in auto-loading pistols, in which the rearward end of the trigger-bar has working movements in transverse directions. A firearm of this 15 class is described in my Patent No. 1,348,733, dated August 3, 1920, granted on my pending application (renewal) Serial No. 311,689, filed July 17, 1919, in which also is described—but not specifically claimed—the 20 improvements which constitute the subject-matter of the present application.

A further object is to provide a trigger mechanism or device in which the trigger is movable rearwardly to move the sear member, and is movable forwardly, and in which 25 the trigger member by a second or subsequent pull thereon to move it rearward, after the first pull, cannot be brought into contact with the sear member to move the 30 sear member unless the trigger is first permitted to move forwardly.

A further object is to provide a trigger mechanism or device having a trigger-bar or thrust member with a retractor-device 35 carried on and by such member, and so organized that the entire trigger mechanism or device may be removed and replaced as a whole. Thus the trigger mechanism or device, although comprising several coactive 40 parts, may be regarded as a single member of the firearm.

For convenience of illustration, the present improvements are herein shown of the same construction, and as being applied to 45 the same form and construction of firearm which is illustrated in said prior application; but it will be understood that said construction, and the manner of applying the device, may be varied within the scope and 50 purview of the present invention.

In the accompanying drawings—

Figure 1 is a side view, partly broken

away to show the details, of a pistol provided with my trigger mechanism or device.

Fig. 2 is a front view, partly in section, on 55 the line 2—2 of Fig. 1.

Fig. 3 is a fragmentary detail sectional view, on larger scale than Fig. 1, of a pistol provided with my trigger mechanism or device, showing the trigger in forward and 60 upward position for engaging the sear member by pull on the trigger to move the sear member, the trigger being moved to and supported in upward position by a slidable member.

Fig. 4 is a top or plan view of my trigger mechanism or device on the line 4—4 of Fig. 1, the slidable member and the sear member being partly in section.

Fig. 5 is a fragmentary detail sectional 70 view on substantially the same scale as Fig. 3, of a pistol provided with my trigger mechanism or device, showing the trigger in rearward and downward position after pull on the trigger to move the sear member, the 75 trigger being moved to and held in such downward position by said slidable member, and not engageable when in this position with the sear member by a second or subsequent pull on the trigger.

Fig. 6 is a top or plan view of the trigger-bar or thrust member of my trigger mechanism or device.

Fig. 7 is a detail plan view of my trigger mechanism or device on the line 7—7 of 85 Fig. 5.

Similar reference characters or numerals refer to similar parts throughout the several views.

My trigger mechanism or device comprises, in its main elements or parts, the slid- 90 able member or controller N, the sear member S, and the trigger F, the magazine lock n, shown but not described herein, being de- 95 scribed in detail, and the grip-safety device G, shown but not described herein, being de- scribed in detail in my said patent.

The slidable member or controller N, only the lower portion thereof being shown for convenience, is located in the pistol rear- 100 wardly of the magazine recess or chamber M and forwardly of and adjacent to the sear member S, and is movable on the frame and grip-stock or handle portion of the pis-

tol, where the frame comprises a grip-stock or handle portion.

The slidable member or controller N is movable in one direction, that is upwardly, by means not shown, but described in my said patent and is movable in a reverse direction, or downwardly, by the sear member S as hereinafter described. The slidable member or controller N is provided with a shoulder 14^p, having twin upper surfaces 14^e, an upper surface 14^e on each side of the slidable member or controller, one side of the slidable member or controller N not being shown in the drawings, but being in all respects similar to the side which is shown herein. The slidable member or controller N is extended below the shoulder 14^p and is provided with twin slots 10, a slot 10 being formed in each side of the slidable member or controller, having a downward face 14^k and an upward face 14^f, the opposite slot 10 not being shown in the drawings but being in all respects similar to the slot which is shown therein. A longitudinal connection or portion 14^b is formed by the slots 10 between the downward faces 14^k and the upward faces 14^f.

The sear member S is pivotally supported on the grip-stock or handle portion of the pistol and has at its upper end an arm S¹⁰ which is split or divided and forms twin arms to straddle or pass on each side of the slidable member or controller N above the shoulder 14^p thereof, the opposite side of the arm S¹⁰ not being shown in the drawings but being in all respects similar to the side which is shown therein. Each twin arm S¹⁰ is provided with an end 17^f, there thus being double or twin end 17^f, the purpose of the ends 17^f being to engage or bear down upon the twin upper surfaces 14^e of the shoulder 14^p of the slidable member or controller N. Each of the twin ends 17^f has an end face 17^d, the end faces 17^d being shown partly in section in Fig. 4.

The trigger F, which is protected by a suitable guard, is mounted preferably in a slidable manner in the grip-stock or handle portion of the pistol, the front end of the trigger being located forward of the magazine recess or chamber M. The trigger F comprises a body portion or thrust-bar portion 11, which extends rearwardly into the slot 2^v of the grip-stock or handle portion of the pistol. The body portion or thrust-bar portion 11 is slotted through as at 6^a forming side bars 6^b 6^b to provide the necessary space and clearance for the cartridge receptacle or holder R which is received in the magazine recess or chamber M and is locked therein by the magazine lock m, the cartridge receptacle or holder passing between the side bars 6^b 6^b, and limiting forward and rearward

movement of the thrust-bar. The slotting also allows for the required movements of the trigger. The side bars 6^b 6^b occupy a slot 2^v (Fig. 5) in the grip-stock or handle portion of the pistol which slot is wider than the side bars 6^b 6^b, so that the trigger F at its rear end 6^c may have an up and down or swinging movement in addition to its normal rearward and forward or longitudinal movements.

The front end of the trigger F is provided with a finger-piece 6^d which is slotted to receive the spring 6^e and the plunger 6^f. The trigger-lever f is pivotally retained in the finger-piece 6^d by a pin 6^g, and is provided with an upwardly extending arm 12, and a forwardly extending arm 13. The arm 12 engages the shoulder 2^v formed in the top wall of a vertical slot in the frame or receiver of the pistol, the shoulder 2^v affording an abutment for the arm 12, and the arm 13 engages the plunger 6^f, the respective engagements of the arms 12 and 13 with the shoulder 2^v and with the plunger 6^f, actuated by the spring 6^e, tending to move the trigger F to forward or normal position. The connection of the spring 6^e and the trigger-lever f holds the trigger F bodily in its forward position, and also tends to hold the rear end of the trigger upward, the forward movement of the trigger F being limited by the curved ends of the side bars 6^b 6^b contacting with or striking the curved ends of the cartridge receptacle or holder R. The rear end 6^c of the trigger F is split or divided, Figs. 4 and 6, to provide twin ends to straddle or pass on each side of the longitudinal connection 14^b of the slidable member or controller N.

Each of these twin ends comprises a recess 6^m and an adjacent extended point or rear-face 6ⁿ, the twin ends being received in the twin slots 10 of the slidable member or controller N and being movable freely between the faces 14^k and 14^f thereof.

To assemble my trigger mechanism or device the trigger F may be introduced as a whole or entire part into the grip-stock or handle portion of the pistol from the rear of the pistol through the slot 2^v, the various impeding or intervening parts not then being in place, and, before the trigger F is moved to its complete forward position, the top end of the trigger-lever f may be revolved or turned forwardly and downwardly so as to be depressed below the top wall of said vertical slot in the frame or receiver of the pistol which receives the front end of the trigger. The slidable member or controller N and the sear member S are then placed in their co-active relation to each other and to the trigger F. The cartridge receptacle or holder R is inserted in the magazine recess or chamber M from the butt of the pis-

tol and between the side bars 6^b 6^b of the trigger F, the cartridge receptacle or holder being retained in place by the magazine lock m. The trigger F may be removed 5 from the pistol as a whole or entire part in a similar way, except that in the course of removal the trigger is moved rearwardly instead of forwardly and in reverse manner, it also being understood that the cartridge 10 receptacle or holder and the slidable member or controller and the sear member, and any other impeding or intervening parts of the pistol, are first withdrawn.

In operation: The slidable member or 15 controller N is moved upwardly as described in my said patent, and the sear member S is moved to firing position as described in my said last mentioned co-pending application. By firing position here is meant the position 20 of the sear member for locking the firing member or hammer H, of the pistol in position for movement to fired position or to discharge the firearm. The twin ends 17^t of the arm S¹⁰ of the sear member are thus 25 out of engagement with the twin upper surfaces 14^e of the shoulder 14^p of the slidable member or controller, and the trigger member F is held in upward and forward position by the slidable member or controller, 30 while the twin end-faces 17^d of the sear member S are in position for engagement with the twin rear-faces 6^a of the trigger F, Fig. 3. Pull upon the finger-piece 6^d of the trigger F moves the trigger rearwardly and 35 the twin rear-faces 6^a thereof into engagement with the twin end-faces 17^d of the sear member and moves the sear member to fired position or to position for releasing the firing member or hammer H of the pistol to fired 40 position. As the sear member S is thus moved to fired position the twin ends 17^t of the arm S¹⁰ thereof engage or bear down upon the twin upper surfaces 14^e of the shoulder 14^p of the slidable member or controller 45 and thereby move the slidable member or controller downwardly, which carries downwardly with it, and holds down, the rear end of the trigger F so that the twin recesses 6^m of the rear end of the trigger 50 are opposite the twin end-faces 17^d of the sear member S, the effect being that the trigger F is then not engageable with the end faces 17^d of the sear member by a second or subsequent pull on the trigger F, 55 Fig. 5, to move the sear member until the trigger F is first moved forwardly by the trigger-lever f, plunger 6^f and spring 6^e, through release of pressure on the finger-piece 6^d of the trigger, and the rear end of 60 the trigger is moved upwardly by upward movement of the slidable member or controller.

Having thus described my invention, I claim:

65 1. In a firearm, in combination, a frame,

a slidable member, a firing mechanism comprising a sear, and a trigger comprising a finger piece and a push-bar; the trigger being loosely supported by the frame and slid- 70 able member for longitudinal movement by pull upon the finger piece for engagement of the push-bar with the sear for moving the sear.

2. In a firearm, in combination, a frame, a 75 slidable member, a firing mechanism comprising a sear, and a trigger comprising a finger-piece and a push-bar, the finger-piece being bodily supported by the push-bar; the trigger being loosely supported by the frame and slidable member for longitudinal move- 80 ment by pull upon the finger-piece for engagement of the push-bar with the sear for moving the sear.

3. In a firearm, in combination, a frame, 85 a slidable member, a firing mechanism comprising a sear, and a trigger comprising a finger-piece and a push-bar, the finger-piece being rigidly connected to the push-bar; the trigger being loosely supported by the frame and slidable member for longitudinal move- 90 ment by pull upon the finger-piece for engagement of the push-bar with the sear for moving the sear.

4. In a firearm, in combination, a frame, 95 a slidable member, a firing mechanism comprising a sear, and a trigger comprising a finger-piece, a push-bar and means connected to the finger-piece and engaging said frame; the trigger being loosely supported by the frame and slidable member for longi- 100 tudinal movement by pull upon the finger-piece for engagement of the push-bar with the sear for moving the sear, and said means connected to the finger-piece and engaging the frame moving the trigger to normal 105 position after pull on the finger-piece.

5. In a firearm, in combination, a frame, 110 a magazine chamber, a cartridge receptacle in said chamber, a slidable member, a firing mechanism comprising a sear, and a trigger comprising a finger-piece, a push-bar straddling the cartridge receptacle, and means connected to the finger-piece and engaging said frame; the trigger being loosely supported by the frame and slidable member for longitudinal movement by pull upon the finger-piece for engagement of the push-bar with the sear for moving the sear, and said means connected to the finger-piece and engaging the frame holding the trigger bodily 115 in forward position.

6. In a firearm, in combination, a frame, a 120 magazine chamber, a cartridge receptacle in said chamber, a slidable member, a firing mechanism comprising a sear, and a trigger comprising a finger piece, a push-bar straddling the cartridge receptacle, and means connected to the finger piece and engaging said frame; the trigger being loosely supported by the frame and slidable member 125 130

for longitudinal movement by pull upon the finger-piece for engagement of the push-bar with the sear for moving the sear, and said means connected to the finger-piece and engaging the frame holding the trigger bodily in forward position and tending to hold the rear end of the push-bar upward.

7. In a firearm, in combination, a frame, a firing mechanism comprising a sear, and a loosely supported trigger operatively arranged for engaging the sear and comprising a finger-piece, a push-bar and means pivotally connected to the finger-piece and engaging said frame for holding the trigger bodily in forward position.

8. In a firearm, in combination, a frame, a firing mechanism comprising a sear, and a loosely supported trigger operatively arranged for engaging the sear and comprising a finger-piece, a push-bar and a spring actuated lever member pivotally connected to the finger-piece and engaging said frame.

9. In a firearm, in combination, a frame, a slidable member, a firing mechanism comprising a sear, and a trigger comprising a finger-piece, a push-bar, and a spring actuated lever member pivotally connected to the finger-piece and engaging said frame; the trigger being loosely supported by the frame and slidable member for longitudinal movement by pull upon the finger-piece for engagement of the push-bar with the sear for moving the sear.

10. In a firearm, in combination, a frame, a slidable member, a firing mechanism comprising a sear, the sear being engageable with the slidable member for moving the slidale member, and a trigger comprising a finger-piece and a push-bar; the trigger being loosely supported by the frame and the slidale member for longitudinal movement by pull upon the finger-piece for engagement of the push-bar with the sear for moving the sear, and the push-bar being movable transversely at the rear end thereof to non-engageable position relative to the sear by the slidale member when the slidale member is moved by the sear subsequent to movement of the sear by the push-bar.

11. In a firearm, in combination, a frame, a slidable member, a firing mechanism comprising a sear, the sear being engageable with the slidale member for moving the slidale member, and a trigger comprising a finger-piece, a push-bar and means connected to the finger-piece and engaging said frame; the trigger being loosely supported by the frame and the slidale member for longitudinal movement by pull upon the finger-piece for engagement of the push-bar with the sear for moving the sear, and the push-bar being movable transversely at the rear end thereof to non-engageable position relative to the sear when the slidale

member is moved by the sear subsequent to movement of the sear by the push-bar, and said means connected to the finger-piece moving the trigger to normal position after pull on the finger-piece when pressure is removed from the finger-piece.

12. In a firearm, in combination, a frame, a slidale member, a firing mechanism comprising a sear, the sear being engageable with the slidale member for moving the slidale member downwardly, and a trigger comprising a finger-piece, a push-bar and means connected to the finger-piece and engaging said frame; the trigger being loosely supported by the frame and the slidale member for longitudinal movement by pull upon the finger-piece for engagement of the push-bar with the sear for moving the sear, and the push-bar being movable transversely downward at the rear end thereof to non-engageable position relative to the sear when the slidale member is moved downwardly by the sear subsequent to movement of the sear by the push-bar, and said means connected to the finger-piece moving the trigger to normal position after pull on the finger-piece when pressure is removed from the finger-piece.

13. In a firearm, in combination, a frame having an opening therein, a slidale member, a firing mechanism comprising a sear, and a trigger loosely supported in said opening of the frame and loosely supported by the slidale member for longitudinal movement of the trigger by pull thereon for engagement with the sear for moving the sear.

14. In a firearm, in combination, a frame having an opening therein, a slidale member, a firing mechanism comprising a sear, and a trigger comprising a finger-piece and a push-bar, the finger-piece being bodily supported by the push-bar, and the push-bar being loosely supported in said opening of the frame and loosely supported by the slidale member for longitudinal movement by pull on the finger-piece for engagement of the push-bar with the sear for moving the sear.

15. In a firearm, in combination, a frame having an opening therein, a slidale member, a firing mechanism comprising a sear, the sear being engageable with the slidale member for moving the slidale member downwardly, and a trigger comprising a finger-piece, a push-bar and a lever member pivotally connected to the finger-piece and engaging said frame, the finger-piece being bodily supported by the push-bar; said push-bar being loosely supported in said opening of the frame and loosely supported by the slidale member for longitudinal movement by pull on the finger piece for engagement of the rear end of the push-bar with the sear for moving the sear, and

the push-bar being movable transversely downward at the rear end thereof to non-engageable position relative to the sear by the slidale member when the slidale mem-
5 ber is moved downwardly by the sear subse-
quent to movement of the sear by the push-
bar, and said lever member moving the trig-

ger to normal position after pull on the fin-
ger piece when pressure is removed from
the finger piece.
